CLAIM

I claim the ornamental design for a lip gloss, as shown and described.

DESCRIPTION

FIG. 1 is a perspective view of a lip gloss showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The “Pudaier” logo in FIGS. 1 and 2 is a registered trademark of Dexin Zhou.
